UNITED STATES PATENT OFFICE

WILLIAM T. KETTERING, OF CHICAGO, ILLINOIS, ASSIGNOR TO FRIELEY-VOSHARDT CO., OF CHICAGO, ILLINOIS, A CORPORATION OF ILLINOIS

DESIGN FOR A LANTERN

Application filed February 20, 1929. Serial No. 30,146. Term of patent 3½ years.

To all whom it may concern:

Be it known that I, WILLIAM T. KETTERING, a citizen of the United States, residing at Chicago, in the county of Cook and State of Illinois, have invented a new, original, and ornamental Design for a Lantern, of which the following is a specification, reference being had to the accompanying drawing, forming part thereof, in which—

Fig. 1 is a perspective view of one side of a

lantern showing my new design, it being understood that the contour and ornamentation of the other two sides are identical with that shown in the perspective view; and Fig. 2 is a bottom view showing contour.

I claim:

The ornamental design for a lantern, as shown and described.

WILLIAM T. KETTERING.
